Attorney

UNITED STATES PATENT OFFICE.

CLYDE C. MEIKELL, OF BETHLEHEM, PENNSYLVANIA.

SHELF.

Application filed December 9, 1921. Serial No. 521,114.

To all whom it may concern:

Be it known that I, CLYDE C. MEIKELL, a citizen of the United States, residing at Bethlehem, in the county of Northampton and State of Pennsylvania, have invented a new and useful Shelf, of which the following is a specification.

This invention is an auxiliary device designed for use with standard store shelving.

10 In mercantile establishments which carry large stocks of shelf goods especially where open shelves are employed, much time and labor is expended in transferring the goods to the shelves, from the cases in which they are shipped. Usually the case is placed on the floor or counter, contiguous to the shelves to be filled, and the goods transferred from this unhandy position. This entails considerable labor, and where the shelves are high, 20 the transfer frequently requires the services of two or more persons. The main object of the invention is to provide an auxiliary shelf, which can be removably supported from any shelf of a stack of shelving, and 25 possessing sufficient stability to sustain the weight of the packing case and its contents, while the goods are being transferred to the permanent shelves.

The invention will be hereinafter fully set 30 forth and particularly pointed out in the claims.

In the accompanying drawing:—

Figure 1 is a perspective view illustrating a portion of a stack of shelving with the invention applied thereto. Figure 2 is a bottom plan view illustrating a form of auxiliary shelf. Figure 3 is a bottom plan view illustrating a slight modification.

Referring to the drawing 10, 10, designate 40 the open shelves of a stack of shelving of any preferred construction, said shelving being divided into compartments by upright division walls 11. Supported by each division wall is a supporting device 12, secured 45 thereto in any suitable manner, said supporting device having an offset portion 13 at its upper end, spaced from the division wall 11.

The auxiliary shelf 14 may be of any desired dimensions, and has a web-like support member 16 secured to its underside, said support member being tapered at its ends, as indicated at 17, and shaped to pass between a division wall 11 and the offset portion 13, 55 of a support member 12. The support and

guide member 16 is secured to the shelf in any desired manner, preferably by screws or the like extending through a flange 18, formed integrally with the web-like portion 16. Said support member is extended rearwardly to form a bearing arm, as shown. The underside of the auxiliary shelf 14 is also provided with spaced apart bearing arms 19, which project beyond the rear edge of said shelf, so as to bear against the underside of the contiguous main shelf 10, to steady the auxiliary shelf in position.

In practice, when it is desired to place goods upon any of the shelves 10, the auxiliary shelf 14 is secured in place, by slidably passing the web 16 beneath the shelf 10 to be filled, between the upright 11 and the offset portion 13 of the support member 12. The rear end or bearing arm of said member 16 extends beneath the shelf 10, and the same is true of the bearing arms 19, so that the shelf is firmly supported upon the support member 12, and steadied by the flange 18 and bearing members 19 pressing against the underside of the shelf 10. The case or package containing the goods to be transferred is then placed upon the auxiliary shelf, in a position to permit convenient transfer of the goods to the permanent shelf 10. After the transfer has been made, the auxiliary shelf may be removed and placed 85 at any convenient storage point for subsequent use.

In Figure 3 is illustrated a slight modification, in which the shelves 10' are provided 90 on their undersides with sleeve-like keepers 20, into which telescope bearing arms 21, secured to the underside of the auxiliary shelf 22. In practice, this auxiliary shelf is used in substantially the same manner as the shelf illustrated in Figures 1 and 2.

The advantages of the invention will be readily apparent to those skilled in the art to which it appertains. It will be particularly noted that by means of the auxiliary shelf, the goods to be transferred to the permanent shelving may be conveniently supported, and handling of the goods is reduced to a minimum. The device is inexpensive and may be applied to any open shelving now in general use. An important advantage is that the auxiliary shelf is engaged and disengaged from the permanent shelf by a sliding movement, and the keepers 105 operate with the arms 16 and 19, or arms 110

21, as the case may be, and the under side of the permanent shelf to sustain the weight of the auxiliary shelf.

Having thus explained the nature of the 5 invention and described an operative manner of constructing and using the same, although without attempting to set forth all of the forms in which it may be made, or all of the forms of its use, what is claimed is:—

- 10 1. A shelf of the character described comprising an auxiliary shelf having spaced apart rearwardly extended bearing arms and an intermediate bearing member, and a keeper constructed to be permanently supported below a fixed shelf, said arms and bearing member being positioned to slidably engage the under side of a permanent shelf, said keeper being positioned to be slidably engaged by said bearing member.
- 15 2. A shelf of the character described comprising an auxiliary shelf having spaced apart rearwardly extended bearing arms and an intermediate bearing member, and a keeper constructed to be permanently supported below a fixed shelf, said arms and bearing member being positioned to slidably engage the under side of a permanent shelf, said keeper being provided with an offset

portion positioned to be slidably engaged by said bearing member.

3. The combination with a supporting member having an offset support portion, of an auxiliary shelf having a weblike support member positioned to slidably engage the offset portion of said supporting member, said support member having a rearwardly extended bearing arm, and a plurality of rearwardly extended bearing arms carried by said shelf, all of said bearing arms being positioned to engage the under surface of a permanent shelf.

4. The combination with permanent shelving having an upright and a support member secured to said upright, of an auxiliary shelf having a supporting member shaped to slidably engage the support member, said supporting member having a rearwardly extended bearing arm positioned to slidably engage the under side of a permanent shelf, and rearwardly extended bearing members carried by the auxiliary shelf and positioned to also engage the under side of said permanent shelving.

In testimony whereof I have hereunto set my hand.

CLYDE C. MEIXELL.
